DESIGN FOR A RAZOR BLADE SHARPENER

John A. Royall, East Boothbay, Maine

Application November 4, 1942, Serial No. 108,691

Term of patent 3½ years

To all whom it may concern:

Be it known that I, John A. Royall, a citizen of the United States, residing at East Boothbay, county of Lincoln, and State of Maine, have invented a new, original, and ornamental Design for a Razor Blade Sharpener, of which the following is a specification, reference being had to the accompanying drawing, forming a part thereof, and in which—

Fig. 1 is a side elevational view of a razor blade sharpener showing my new design; and

Fig. 2 is a vertical sectional view taken substantially through the center thereof.

I claim:

The ornamental design for a razor blade sharpener, as shown.

JOHN A. ROYALL.
